United States Patent Office

Des. 196,541
Patented Oct. 8, 1963

196,541

PACKAGE OF BUBBLE-BLOWING FLUID OR THE LIKE

Jerome B. Kalish, Chicago, Ill., assignor to
Chemical Sundries Co., Chicago, Ill.

Filed Nov. 1, 1962, Ser. No. 72,345

Term of patent 7 years

(Cl. D58—26)

FIG. 1

FIG. 2

FIG. 3

FIG. 4

FIG. 1 is a front elevational view of a package showing my new design;

FIG. 2 is an end elevational view thereof, the opposite end view being the same;

FIG. 3 is a top plan view; and

FIG. 4 is a bottom plan view.

I claim:

The new and ornamental design for a package of bubble-blowing fluid or the like, substantially as shown and described.
